COUPLING SLEEVE

Lawrence M. Curtiss, Mountainside, N.J., assignor to
The Thomas & Betts Co., Elizabeth, N.J., a corpora-
tion of New Jersey

Filed Feb. 3, 1959, Ser. No. 54,443

Term of patent 14 years

(Cl. D91—3)

Fig. 1

Fig. 2

Fig. 4

Fig. 3

Fig. 5

Fig. 1 is a top plan view of the coupling sleeve showing my new design;

Fig. 2 is a side view in elevation of the coupling sleeve design as rotated 90 degrees from that shown in Fig. 1;

Fig. 3 is an end view of the coupling sleeve design shown in Fig. 2;

Fig. 4 is a longitudinal sectional view taken on the line 4-4 of Fig. 3; and

Fig. 5 is a transverse sectional view taken on the line 5-5 of Fig. 2;

I claim:

The ornamental design for a coupling sleeve, as shown.
